BASEBALL GAME

Maximilian C. Meyer, Brooklyn, N. Y.

Application August 21, 1943, Serial No. 499,522

7 Claims. (Cl. 273—93)

1

My invention relates to a novel educational and recreational baseball game and more particularly my invention relates to a baseball game that is mechanically operated but is substantially entirely governed by the discretionary acts of judgment exercised in playing the game of baseball.

Many games based on baseball have been proposed but they have lacked public acceptance primarily because they are baseball games in name only and have no realistic relation to the game of baseball as it is known and played by substantially all American men and boys. Although the prospective user may be drawn to such games because of their appearance or because they are called baseball games, any specific examination soon makes evident the fact that the playing of the game basically depends on pure chance alone as exemplified by the use of a spinner dial and no baseball strategy or judgment is required or useful in their playing.

It is the object of my invention to provide a novel baseball game that can be played by two individuals or two teams in such a manner that the team that exercises the superior baseball judgment and strategy will have the advantage over its opponent in the same way that superior judgment and strategy will constitute an advantage in the ordinary game of baseball.

It is the further object of the present invention to provide a novel baseball game that embodies in mechanical form a true reincarnation of baseball as played on the diamond.

It is a further object of my invention to provide a novel mechanical baseball game in which a pitcher can exercise his own discretion and present to the batter a variety of pitches according to his judgment.

It is a further object of my present invention to provide a novel mechanical baseball game in which the batter can, through the exercise of his own discretion, decide whether to hit at or "take" the ball delivered by the pitcher.

It is the further object of my invention to provide a mechanical baseball game in which the batter can exercise his judgment as to the kind of pitch that the pitcher is delivering and govern his own response accordingly as is the practice in the playing of the actual game of baseball.

It is the further object of my invention to provide a mechanical game of baseball in which various moves can be made effectively or which correspond generally to the baseball strategy in the ordinary game of baseball.

It is a further object of my invention to provide a novel mechanical game in which a ball may

2

be delivered into a rotating element comprising a series of separate compartments in such a manner that the ball will remain within that element and quickly settle in one compartment thereof.

I accomplish these objects by a mechanical game in which a batting stand is provided on a board adjacent to a rotatable wheel. The pitcher places a ball, while concealed from the batter, into a selected hole or slot according to whether he wishes to pitch a ball or a strike, and he may also elect whether the ball will be an incurve or an outcurve. A batter can either decide to hit at the ball, or to "take" the ball. If he takes the ball then he is credited with the ball or charged with a strike, depending on whether the pitcher delivered a ball or strike. If he strikes at the ball, then he must judge as to whether the pitcher delivered an incurve, straight ball or an outcurve, and tap a corresponding plunger device. If he guesses incorrectly, he is charged with a strike because the plunger will not contact the ball. If he guesses correctly, then the plunger discharges the ball from the opening into the rotating wheel, where, as in ordinary baseball, upon the ball being hit out into the field, a safe hit or an out may result.

Both the pitcher's actions and the batter's actions are determined by the number of strikes, 30 balls, the outs, and the presence of men on bases.

The side at bat may elect to attempt to steal when their runner is on base and are provided with means for determining whether or not such steals are successful.

Strategy in judgment that plays so important a part in ordinary base ball, plays an equally important part in this game.

The game itself and the baseball judgment and the strategy that may be exercised in the playing 40 of the game will best be understood from consideration of the drawings and the specific description which here follows:

Figure 1 is a plan view of the game of my invention.

Figure 2 is a side view of the game looking towards the rear side of the pitching and batting stand which is the side which the pitcher faces in delivering the ball.

Figure 3 is a cross section taken along line 3—3 of Figure 1.

Figure 4 is a plan view of the element that conceals the pitcher's actions from the batter's, the element also carrying certain information as 55 to the playing of the game.

Figure 5 is a cross section taken along line 5-5 of Figure 1.

Figure 6 is a cross section taken along line 6-6 of Figure 1.

Referring now more specifically to the drawings in Figure 1, I show a base 10 on which is mounted a wheel element generally referred to as 11 which is rotatably mounted on pin 13 (see Figure 3) which is fastened to the base 10, the washer or bearing elements 14 being provided to allow the free rotation of the wheel element 11 on the pin 13. A central knob 15 is provided to enable the player to rotate the wheel element 11 by hand.

The wheel element 11 is divided into a plurality of compartments 16 which are separated by slats 17 so that a ball element 18 on being delivered to the wheel element will come to rest within one of the compartments 16.

Three pointer elements 20, 21 and 22 are provided at positions corresponding to second base, third base and home plate. The peripheral wall of each compartment 16 is made up of a wall element 24. The outside appearance of this wall element 24 will be seen in Figure 2, and the inside appearance of wall element 24 will be seen in Figures 3, 5, and 6 and discussed hereinafter. The knob 15 is mounted on a circular dome-shaped element 26 and a plurality of discs 27 are set into dome member 26. These disc elements have certain double play designations that are employed when batters are on such base positions as would make them susceptible to the operation of a double play.

Mounted on base 10 is a pitching and batting stand 30 through which protrude certain striking elements which the batter may elect to tap. One is an in-curve-ball element 31; another a straight-fast-strike-element 32; and the third is an out-curve-ball element 33. The structure and operation of these elements will be evident from the showing thereof in Figures 2 and 3 and the description thereof which follows in connection with the description of the operation and playing of this game.

In positions corresponding to first base, second base, and third base respectively are peg receptacles 35, 36, and 37 in which may be placed suitable pegs that are provided for use in this game to indicate player positions. An out indicator is provided in one corner of the board 38 which contains three holes indicated as 39 in which by the placement of a peg the number of outs counted against a side may be recorded.

The mechanical operation of the device is indicated best in Figure 3. By means of thumb and forefinger applied to the knob 15, the wheel element 24 is caused to rotate on the pin 13 in a counter-clockwise direction. The batter, when he has decided to strike at a ball decides what kind of a pitch has been delivered by the pitcher and taps according to that choice one of the elements such as 32. Element 32 comprises a plunger 40 which is yieldably held by a spring 41 and has a rounded or slanted bottom 42. The plunger 40 has a knob top so that the finger can easily be applied thereto and when tapped downwardly the rounded or slanted end 42 of the plunger 40 strikes the ball 18 on the rear side thereof. Thus, while impelling the ball outwardly from the groove 43 it imparts a backward spin to the ball 18 as indicated by the arrows on the ball in its intermediary position at 48. The spring 41 and the distance between the knob on the end of the striking element 32 and the stand 30 is such that

within a substantial range of definite impacts by tapping of the element 32, the ball 18 will be caused to fall on the dome element 26 or within the wheel element 11. The back spin imparted to the ball 18 is a prime factor in preventing the ball 18 from bouncing out of the wheel element 11. It is important that the ball 18 stay in the wheel element 11 since otherwise a replay is necessary.

The playing of the game is as follows:

The rules of the national game of baseball are employed wherever possible. The batter is out on three strikes but goes to base on four balls. Nine innings constitute a game and in the event of a tie, play is continued until a difference of at least one run between the two sides is found at the end of an inning.

The game is begun by the pitcher who acts for one side and who, after deciding to pitch a ball 15 or strike, places the ball 18 in one of the concealed holes 43, 44 or 45 (see Figure 2). A groove 47 is provided which encompasses the three holes 43, 44, 45 so that the ball 18 for the deception of the batter, may be moved back and forth by the pitcher in that groove 47 just before he allows the ball 18 to drop into one or the other of the holes. The batter is prevented from seeing into which hole the pitcher has dropped the ball 18 because of the intervention of the pitching batting stand 30 and because of the intervening screen element 50. (See Figures 3 and 4.)

The batter takes his position for this purpose facing that side of the screen 50 on which the elements 32 are located while the pitcher takes his side on the opposite side of the screen 50 where the pitching groove 47 is located. The pitcher then having elected as to what kind of pitch he will deliver drops the ball 18 into the hole 45 if he wishes to throw an in-curve-ball or into the hole 43 if he wishes to throw straight-fast-strike, or into the hole 44 if he wishes to throw an out-curve-ball.

The batter exercises his judgment to determine the type of ball the pitcher has delivered and then either raises his forefinger to give the signal that he is "taking" the pitch without striking at it, in which case, if the ball has been deposited in the holes 44 or 45 he is given credit for a ball, whereas if the pitcher has deposited the ball in hole 43 a strike is counted against him. If he elects to strike at the ball then he must again determine through the exercise of his judgment as to what kind of pitch the pitcher has delivered, the decision involved depending upon the number of balls or strikes and number of outs, and the number of men on bases. Having decided as to whether the pitch is an in-curve, out-curve, or a straight fast ball, he taps the corresponding plunger element 31, 32, or 33. If he has calculated correctly, and for example, taps the middle plunger 32 and the pitcher has delivered a straight fast ball (having dropped the ball in the hole 43) then his tapping the element 32 causes the ball to be expelled as shown in Figure 3 out into the wheel element 11. The ball 18 then drops into one of the compartments 16. The notation on the inside wall 24 of the compartment 16 indicates, as seen in Figures 3, 5, and 6, whether he has gotten a hit such as a single, triple or a home run, or an out has resulted. As can be seen by an examination of the plan view in Figure 1, each compartment 16 contains a notation as to where the ball has gone,

e. g. to center field, or in the case of an out, the players that have executed that out.

The batter, if he has obtained a safe hit, is represented by a peg being placed in the corresponding base, e. g., first base 35 and third base 37. The next batter then steps up and the process is repeated, the pitcher and the batter now both being governed in their actions by the presence of the man on base.

When the ball is not hit at or is missed, the man at bat returns the ball to the pitcher by tapping the plunger element indicated by the pitcher. If during the play, the ball strikes the element 11 in such a way that the ball does not stay within the wheel element 11, then a foul ball and the consequent strikes are counted up against the batter up to and including the second strike.

The side at bat may attempt to steal if it has a runner or runners on base. The batter must announce this when the ball is delivered. If the batter strikes at the ball and misses during the attempt at steal or if he "takes" the pitch, then the outcome of the steal is determined by the indicator at the batter's base involved. The indicators are 20 at second base, 21 at third base and 22 at home plate. The result of the attempt is determined by whether the appropriate base indicator points as seen in Figure 2 to "out" or to "safe."

The double play discs 27 which are mounted on the dome 26 are placed immediately adjacent certain of the compartments 16. For example the disc denoted as 27 in Figure 1 is placed immediately at the head of the compartment carrying the numbers 6-3. This disc is employed when a runner is on first base, for in that case when the batter hits the ball into this compartment the shortstop 6 throws the ball to the second baseman 4, thus forcing the runner on first base, the second baseman 4 then throwing the ball to the first baseman 3 who puts out the batter. A double play is thus effected. If there is no runner on first base then this double play indication has no part in the play. Double plays, as in baseball, are effective when there is no more than one out on a side.

The various other rules that apply to baseball are utilized in this game.

The present game is of great value not only for the recreational value to those who enjoy the game of baseball because of its basic relationship to the game of baseball, but also because of its educational value. The various strategies and judgments of baseball may be exercised and developed by those who play this game so that the mental background and acts of judgment and strategy are developed for use on the baseball field by the player.

It will be apparent to those skilled in the art that the novel principles of the invention disclosed herein in connection with the specific exemplifications thereof will suggest various other modifications and applications of the same. It is accordingly desired that in construing the breadth of the appended claims they shall not be limited to the specific exemplifications of the invention described herein.

I claim:

1. In a baseball game in which a ball is propelled into a wheel element containing a plurality of separate compartments, which wheel element is adapted to be rotated, a pitching and batting stand rising above and positioned adjacent to said wheel element, a plurality of holes

on the pitching side of said stand, which pitching side faces said wheel element, said holes being adapted to receive and hold a ball when placed therein, a plurality of propelling elements disposed in said pitching and batting stand, one for each of said holes, a plurality of means positioned on the batting side of said pitching and batting stand for actuating said propelling elements, each of said means being adapted to actuate a corresponding one of said propelling elements to cause a ball in the corresponding hole on the pitching side to be propelled into said compartmented wheel, and means for concealing from the batting side the area including and surrounding the holes in the pitching side in which said ball is adapted to be placed.

2. In a baseball game in which a ball is propelled into a wheel element containing a plurality of separate compartments, which wheel element is adapted to be rotated, a pitching and batting stand rising above and positioned adjacent to said wheel element, a plurality of holes on the pitching side of said stand facing said wheel element, a plurality of plungers on the opposite or batting side of said stand, one plunger for each of said holes, each of said plungers being positioned to extend into one of said holes, said ball being adapted to be placed into any one of said holes, each of said plungers being so positioned that it may be moved into contact with said ball when in its respective hole, whereupon said ball is expelled into said wheel element and settles into one of the separate compartments thereof.

3. In a baseball game in which a ball is propelled into a wheel element containing a plurality of separate compartments, which wheel element is adapted to be rotated, a pitching and batting stand rising above and positioned adjacent to said wheel element and being mounted on a support, said stand having on opposite sides a pitching side and a batting side, said pitching side being concealed from said batting side, a plurality of holes in the pitching side facing said wheel element, said ball being adapted to be placed in any one of said holes, a plurality of plungers on the batting side one plunger for each of said holes, each of said plungers being yieldably supported so that the tapping of a selected plunger moves one end of said plunger into its respective hole and thereby expels the ball from the hole into said wheel element.

4. In a baseball game in which a ball is propelled into a wheel element containing a plurality of separate compartments, which wheel element is adapted to be rotated, a pitching and batting stand rising above and positioned adjacent to said wheel element and being mounted on a support, said stand having on opposite sides a pitching side and a batting side, said pitching side being concealed from said batting side, a plurality of holes in the pitching side facing said wheel element, said ball being adapted to be placed in any one of said holes, a plurality of plungers on the batting side, one plunger for each of said holes, each of said plungers being yieldably supported with one end moveable downwardly into its respective hole through a channel communicating with the innermost end thereof so that the tapping of a selected plunger moves one end of said plunger down into its respective hole, the movement of said plunger being such as to expel the ball which has been placed in the hole associated with the plunger which is tapped into said wheel element with a

backspin on said ball imparted thereto by said plunger.

5. In a baseball game in which a ball is propelled into a wheel element containing a plurality of separate compartments, which wheel element is adapted to be rotated, a pitching and batting stand rising above and positioned adjacent to said wheel element and being mounted on a support, said stand having on opposite sides a pitching side and a batting side, said pitching side being concealed from said batting side, a groove which includes along its length a plurality of holes in the pitching side facing said wheel element, said ball being adapted to be placed in any one of said holes, a plurality of plungers on the batting side one plunger for each of said holes, each of said plungers being yieldably supported so that the tapping of a selected plunger moves one end of said plunger into its respective hole, the movement of said plunger being such as to expel the ball which has been placed in the hole associated with the plunger which is tapped into said wheel element.

6. In a baseball game which includes a plurality of compartments for receiving a propelled ball; a stand having a pitching side and a batting side, the pitching side facing the said compartments, a plurality of openings located in said pitching side each adapted to receive a ball, a plurality of impelling means corresponding to the number of said openings and a separate one of said impelling means associated with each of said openings and adapted to impel a ball when located in the corresponding opening into the air with the proper force in the direction of the said compartments, a plurality of actuating means for operating the impelling means from the batting side of the stand, one actuating means being associated with each impelling means and its cor-

responding opening, and means for concealing the openings in the pitching side of the stand from the batting side.

7. In a baseball game which includes a plurality of compartments for receiving a propelled ball; a stand having a pitching side and a batting side, the pitching side facing the said compartments, a plurality of openings located in said pitching side each adapted to receive a ball, a plurality of impelling means corresponding to the number of said openings and a separate one of said impelling means associated with each of said openings and adapted to impel a ball when located in its opening into the air with the proper force in the direction of the said compartments, an actuating element associated with each of the impelling means, which element extends to and is operable from the batting side of the stand, and means for concealing the openings in the pitching side of the stand from the batting side.
